UNITED STATES PATENT OFFICE.

LUPPE LUPPEN, OF PEKIN, ILLINOIS.

CULTIVATOR.

SPECIFICATION forming part of Letters Patent No. 508,481, dated November 14, 1893.

Application filed January 9, 1893. Serial No. 457,843. (No model.)

To all whom it may concern:

Be it known that I, LUPPE LUPPEN, a citizen of the United States, residing at Pekin, in the county of Tazewell and State of Illinois, have invented certain new and useful Improvements in Cultivators, of which the following is a specification, reference being had to the accompanying drawings, in which—

Figure 1 is a side elevation, one wheel being removed. Fig. 2 is a top or plan view. Fig. 3 is a rear elevation. Fig. 4 is an enlarged detail, being a plan view of one of the disk gangs. Fig. 5 is an enlarged detail, being a rear view of the parts shown in Fig. 4. Fig. 6 is an enlarged detail, being a section on line 6—6 of Fig. 5. Fig. 7 is an enlarged detail, being a section on line 7—7 of Fig. 4. Fig. 8 is a plan view of the disk gangs showing them arranged for throwing the dirt outward; and Fig. 9 is a rear view of the parts shown in Fig. 8.

My invention relates to cultivators, and particularly to disk cultivators.

The objects of my invention are to provide improved devices for mounting the disks, whereby they may be easily adjusted to the line of motion of the cultivator for the purpose of regulating the furrows; to provide means whereby the disks may be arranged for throwing the dirt either in or out; to provide means whereby the depth of the furrows may be regulated at pleasure, and to improve the construction of cultivators of this class in general. I accomplish these objects as hereinafter specified and as illustrated in the drawings.

That which I regard as new will be pointed out in the claims.

In the drawings,—10 indicates a cultivator, the frame of which consists of a tongue 11, wheel axle 12, wheels 13 and 14, seat bars 15 and 16, draft bar 17, and braces 18 and 19. The draft bar 17 is mounted upon the tongue 12 near its rear end in the usual manner, and is provided with depending hangers 20 near its ends, as shown in Fig. 1. The braces 18 and 19 extend from opposite sides of the tongue 11 to the wheel axle 12, to which they are connected, as best shown in Fig. 2, and serve to brace the tongue. The seat bars 15 and 16 are connected at their forward ends

to the braces 18 and 19, and carry a seat 21 at their rear ends, as shown in Figs. 1 and 2.

22 indicates an arched axle which constitutes a front support for the frames of the 55 disk gangs and is mounted upon the rear end of the tongue 11, and provided with spindles 23 and 24 located in front of and slightly below the spindles of the wheels 13 and 14, as best shown in Fig. 1.

25 and 26 indicate sleeves or pipe-boxes, mounted respectively upon the spindles 23 and 24, as shown in Fig. 2. Each pipe-box is provided with one or more bolt-holes 27, by means of which the cultivator couplings may 65 be coupled to the pipe-boxes, as will be hereinafter described.

28 and 29 indicate brace rods connected at their rear ends to the ends of the axle 22, and at their forward ends to the tongue 11, as 70 shown in Fig. 2.

30 and 31 indicate draft rods, connected at their rear ends to the spindles 23 and 24 and at their forward ends to the hangers 20, as shown in Figs. 1 and 2.

32 and 33 indicate rods which connect the ends of the spindles 23 and 24 with the ends of the wheel axle 12, as best shown in Figs. 2 and 3.

34 and 35 indicate cultivator gangs, which 80 are mounted under the wheel axle 12 and are connected at their forward ends to the pipe-boxes 25 and 26 by means of couplings 36, as best shown in Figs. 1 and 4. Each coupling 36 consists of a link 37, which is pivotally connected to one of the pipe-boxes 25 or 26 by means of a bolt 38, which passes through bolt holes in the forward portion of the link and through one of the holes 27 in the pipe-box.

Rigidly connected to each link 37 is a foot-lever 39, which extends rearward therefrom substantially in a horizontal position, and is provided with a foot-rest 40, as shown in Fig. 1. The foot lever 39 is adjustably secured upon its link 37, and for this purpose I prefer to use a clutch 41 composed of two clutch-sections adapted to be held tightly together by a bolt 42, as best shown in Fig. 1. By loosening the bolt 42 the position of the lever 39 with reference to the link 37 may be adjusted as desired.

Each disk gang 34 and 35 consists of a frame

43, having depending arms 44 and 45, by which are supported disks 46, as best shown in Fig. 5. Mounted upon each disk frame 43 at one end of the rear portion thereof is a horizontal plate 47, as best shown in Fig. 5.

48 indicates a second plate, which is adapted to rest upon the plate 47, which plate 48 is provided with an upwardly projecting arm 49, as shown in Fig. 5. The plates 47 and 48 are secured together and to the disk frames 43 by bolts 50, which pass through said plates and through bolt-holes 51 provided in the upper surface of the rear portion of the disk frames 43. A number of holes 51 are provided in the disk frames 43 to permit of adjusting the position of the plates 47 and 48. The plates 47 and 48 are adapted to turn upon each other to permit of the adjustment of the frames 43 to the line of motion of the cultivator.

52 indicates an arch, best shown in Fig. 3, which arch connects the arms 49 carried by the two disk frames 43, as best shown in Fig. 3. The lower ends of the arch 52 are secured to their respective arms 49 by bolts 53, in such manner as to permit of the turning of said arms upon the bolts 53 as their axes. Near the upper portions of the arms 49 are provided bolt holes 54 adapted to receive a pin 55 which is adapted to pass through the arch 52 into the holes 54 to permit of adjusting the angular position of the arms 49 to the arch 52, and thereby providing for the vertical adjustment of the cultivating disks, as indicated by the dotted lines in Fig. 5.

The disk frames 43 are provided at their forward ends with bolts 56 fitted in slots 57 in plates 58, in such manner that the disk frames 43 may be partially rotated on a horizontal axis without moving the plates 58. Each plate 58 is provided with bosses 59 and 60 adapted to receive a bolt 61, which passes through suitable holes in the rear portion of the link 37, as shown in Fig. 1. By this construction lateral swinging of the disk frames 43 is permitted.

At some suitable point upon each disk frame 43 is provided a bracket 62, which is provided with a horizontal slot, as shown in Fig. 3, through which slot the lever 39 passes, as best shown in Fig. 3. Each bracket 62 is provided with bolt holes 63 arranged at suitable points on its upper surface, as shown in Fig. 3.

64 and 65 indicate levers for adjusting the height of the disk gangs. The levers 64 and 65 are mounted at opposite sides of the cultivator frame, and each lever is connected through a rigid connecting rod 66 to the bracket 63 which lies under it, by a bolt 67. By adjusting the point of connection of the rod 66 with the bracket 63 the action of the lifting lever may be varied.

68 indicates segmental racks adapted to receive pawls 69 carried by the levers 64 and 65, for locking the levers in position.

By connecting the levers 64 and 65 with

the disk-carrying frames through the medium of rigid connecting rods 66, a positive downward pressure may be exerted upon the gangs 70 separately, thereby forcing them into the ground, and by locking levers the disk gangs may be held at any desired depth. If it is desired to hold the gangs in the ground in an inclined position, the connecting rods 66 are 75 connected to the brackets 62 at one end or the other, depending upon the direction of inclination in which the gangs are to be held. The arrangement described enables the entire weight of the machine and rider to be thrown 80 upon the disk-carrying frames, thereby securing a very efficient machine.

The operation of the cultivator is as follows: When the cultivating disks 46 are not in use, the levers 64 and 65 are thrown back, thereby 85 lifting the disks from the earth, the pipe-boxes 25 and 26 turning upon their spindles 23 and 24 and thereby permitting of such lifting of the cultivating disks. For throwing the dirt in, the disks are arranged as shown 90 in Fig. 2, and the extent to which they will throw the dirt in will be determined by their angle to the line of motion of the cultivator. By moving the foot lever 36 laterally the forward portion of the disk frames will be 95 thrown in in the same direction in which the foot lever is moved, thereby throwing the forward edges of the disks also in a similar direction, as indicated by dotted lines in Fig. 4. By the peculiar arrangement of the 100 coupling devices by means of which the forward ends of the gangs are shifted to adjust the position of the disks, a much greater leverage is obtained and the foot levers are relieved from the greater portion of the strain 105 upon the cultivating disks. The operator is thereby enabled to hold the foot lever at any desired position by a slight pressure of the foot. This permits of very accurate and rapid adjustment of the disks and facilitates 110 the avoidance of obstructions. As the disks are adjusted to the line of motion, the plates 47 and 48 will turn upon each other as may be necessary. When it is desired to change the depth of the furrows so that they will not 115 all be of equal depth, the cultivating disks may be thrown into an inclined position by adjusting the angle of the arms 49 to the arch 52, as indicated by dotted lines in Fig. 5. Such rotation of the disk frames as may be 120 necessary on account of such adjustment of the disks will be permitted by reason of the construction of the plates 58, as shown in Fig. 7. To arrange the disks for throwing the dirt outward, the plates 47 and 48 are 125 moved to the opposite ends of the disk frames 43, as shown in Figs. 8 and 9, and the disk gangs 34 and 35 exchange places; that is, the gang 34 is moved to the left hand side of the machine, as shown in Fig. 3, and the gang 35 130 to the right hand side. The parts will then be in the position shown in Figs. 8 and 9. By adjusting the position of the plates 47 and 48 upon the disk frames 43, the action of the

foot levers 39 may be varied to cause them to be moved a greater or less amount by the same movement of the foot levers.

Although in my improved cultivator disks 5 are used for cultivating purposes, I do not wish to limit myself to the use of disks, as other suitable cultivating devices may be used. Neither do I wish to limit myself to the use of coupling links of the specific construction shown, as other devices could be used to accomplish the same result. The form shown, however, is the best known to me at present.

By constructing the cultivator as above described, it is particularly adapted for use in hard soil or in replanted corn, as without leaving his seat the operator may cause the dirt to be thrown high or low by means of the foot lever, and the disks can be held in the ground at any desired depth while the cultivator is in motion, even though there may be hard parts and sandy soil in the same row. A peculiar advantage lies in the fact that the operator can operate the disks by means of 25 the foot lever to dodge corn, at the same time leaving his hands free to handle the lines.

That which I claim as my invention, and desire to secure by Letters Patent, is—

1. The combination with a carriage, and a front support, of a laterally-movable disk frame, having a jointed connection at its front end with the said support, and a laterally-movable lever rigidly connected to said jointed connection, and serving to move the disk frame and the forward edges of the disks 35 in the same direction in which the lever is moved, substantially as described.

2. The combination with a carriage, and a front support, of laterally-movable disk-carrying frames, each having an independent jointed connection with the front support, and laterally-movable rigid levers rigidly attached to said jointed connections, and serving to move the disk-carrying frames and the forward edges of the disks in the same direction 45 in which the levers are moved, substantially as described.

3. The combination with a frame, as 43, of a link, as 36, pivotally connected to the forward end of said frame, supporting devices pivotally supporting and permitting lateral motion of said link, and a lever for operating said link to adjust the frame to the line of motion, substantially as described.

4. The combination with a carriage, a front support, and laterally-movable disk-carrying frames, of links pivotally connected to the front support and to the forward ends of the disk-carrying frames, and a lever rigidly attached to each 55 of said links for moving the latter laterally, and thereby shifting the angle of the disks relatively to the line of motion, substantially as described.

5. The combination with a carriage, a front arch 22, and pipe boxes 25 mounted on parts 65 of the arch, of laterally-movable disk-carry-

ing frames 43, coupling links 37, pivoted to the pipe boxes and to the forward ends of the disk-carrying frames, and levers rigidly connected to the links for shifting them laterally, 70 and thereby adjusting the position of the disks relatively to the line of motion, substantially as described.

6. The combination with an arch 52, disk frames 43 secured thereto, plates 47 and 48 75 carried by said frames, arms 49 carried by said plates 48, means for securing said plates to said arch, and devices supporting the forward ends of said disk frames, of means for moving the forward ends of said disk frames 80 laterally to adjust the position of the disks with reference to the line of motion, substantially as described.

7. The combination with a carriage, a front arch 22, and pipe boxes 25 carried by parts 85 of said arch, of laterally-movable frames 43, provided with cultivating devices, laterally-swinging coupling links 37 pivoted to the pipe boxes and to the forward ends of the laterally-movable frames, and a rigid foot-lever rigidly 90 attached to each of said links for shifting the same laterally, and thereby adjusting the position of the frame with respect to the line of motion, substantially as described.

8. The combination with a front support, 95 and a laterally-swinging link pivotally connected at its front end with said support, of a laterally-movable cultivator frame pivoted to the rear end of said coupling and rotatable on a horizontal axis, and also adapted to tilt 100 in a vertical plane, substantially as described.

9. The combination with a carriage, and a front support, of a laterally-swinging coupling link pivotally connected with the front support, a cultivator frame pivoted to the link 105 to rotate on a horizontal axis, and shifted laterally by the lateral movement of the link, a rear support to which the cultivator frame is pivotally connected to tilt in a vertical plane, and means for shifting the link laterally, 110 substantially as described.

10. The combination with a carriage, and a front support, of a laterally-swinging link pivotally connected with the front support, a cultivator frame pivoted to the rear portion 115 of the link to rotate on a horizontal axis, and moved laterally by the lateral movement of the link, a rear support to which the cultivator frame is connected by a duplex joint, so that said frame can tilt in a vertical plane, 120 and a lever rigidly connected with the movable link for shifting the same, and thereby adjusting the cultivator frame laterally, substantially as described.

11. The combination with a front support 125 22, having a pipe box 25, of a laterally-swinging link 37, adjustably pivoted at its front end to the pipe box, a cultivator frame pivoted to the rear end of the link to rotate on a horizontal axis, a rear support 52, a duplex 130 pivotal connection between the rear support and the cultivator frame, and a lever rigidly

attached to the said laterally-swinging link for operating the same to shift the cultivator frame laterally, substantially as described.

12. The combination with a carriage, and a front support 22, of a pipe box 25 mounted on a part of the front support, a laterally-swinging link 37 pivoted to and adjustable to different positions along the said pipe box, a cultivator frame 43 pivoted to the link, and shifted laterally by the laterally-swinging movement of the link, a rear support having a pivotal connection with the rear end portion of the cultivator frame, and a rigid foot-lever rigidly attached to the laterally-swinging link for operating the latter to adjust the cultivator frame laterally, substantially as described.

13. The combination with a carriage, and a

front support 22, having a pipe box 25, of a laterally-swinging link 37 pivoted to the pipe box, a cultivator frame, having a slotted plate 58 adjustably connected with the said link for rotating the cultivator frame on a horizontal axis, a rear support 52, and plates 47 and 48 pivotally connected together, one of which is provided with an arm 49 adjustably connected with the said rear support for enabling the cultivator frame to move laterally, and also to tilt in a vertical plane, substantially as described.
